TUFTING ATTACHMENT FOR SEWING MACHINES

Julian Guy Russell, North Chattanooga, Tenn., assignor, by mesne assignments, to Carter Brothers, Incorporated, Chattanooga, Tenn., a corporation of Tennessee

Application December 9, 1929, Serial No. 412,821
Renewed July 19, 1933

34 Claims. (Cl. 112—79)

The invention relates to improvements in tufting attachments for sewing machines for making tufted work on sheeting or woven fabrics, and the present application embodies improvements on the machine set forth in the patent of 5 J. M. Gladish, No. 1,575,570, dated March 2, 1926.

The present device embodies many of the features of the patent referred to, with certain 10 additional elements which cooperate with and improve the operation of the former machine.

The prior machine was designed to produce a series of loops or tufts in regular sequence in sheeting or fabrics. This machine included a 15 reciprocating needle carrying a strand of yarn or thread, and operating to produce and secure successive loops in stitch-like form in the fabric. The loop forming mechanism included a bill or looper reciprocating toward and from a fixed 20 abutment, the bill being designed to pass between the needle and the strand carried thereby while the needle was in lowered position. Co- 25 operating with the looper bill in the formation of the loop was a reciprocating loop retainer or gripper arm, which gripped or engaged a portion 30 of the loop against a stationary abutment or stud during a part of the looping operation, which gripper arm, in addition to its reciprocating movement toward and from the fixed abutment, 35 also had a swinging movement substantially at right angles to the reciprocating movement, thereby sliding the yarn or thread on the face of the stud or abutment, which operation was accompanied by considerable friction, and in some cases the stitches were pulled out of the 40 goods. The present invention is intended to overcome these defects.

One of the objects of the invention, therefore, 45 is to provide an oscillating gripper rest which cooperates with a gripper arm or loop retainer similar to that employed in the Gladish patent. By the use of the oscillating gripper in place of a stationary stud, as in prior practice, friction is done away with, and it is possible to grip the 50 yarn employed for making the tufts much more tightly than in prior practice, without any danger of pulling the yarn out of material being sewed.

Another feature of the present invention is an 55 auxiliary gripper which cooperates with the gripper previously employed and prevents the yarn from pulling out of the material while the needle is making an upward stroke. This gripper works against a stationary stud or abutment, and has

an oscillating movement toward and from the stud.

Another object of the invention is to provide an adjustable rest for the looper bill or loop forming mechanism, so that a snug fit between 5 the looper and its rest may be obtained.

Another object of the invention is to provide an improved means for varying at will the length 10 of stitches, such means according to the present embodiment of the invention comprising a yoke 15 which may engage with any one of a plurality of cams of different dimensions.

A further object of the invention is to improve the throat plate of the machine, and preferably 15 also the presser foot, by providing means which cause the stitches previously formed in the material being sewed upon to enter grooves which 20 guide the stitches and keep them out of the way of the needle which is now forming another line of stitching.

Another object of the invention is the improvement of the looper bill and the looper rest 25 which cooperates therewith.

Other objects of the invention will appear from the following detailed description and the accompanying drawings.

The invention will be more readily understood by reference to the accompanying drawings, setting forth a preferred embodiment of the invention.

In the drawings

Fig. 1 is a side elevation of a sewing machine with the improved mechanism constituting the invention applied thereto, and the enclosing means or work support removed;

Fig. 2 is a horizontal section of a part of the sewing machine below the presser foot and throat plate;

Fig. 3 is a transverse vertical section on an enlarged scale on the line 3—3 of Fig. 2;

Fig. 4 is a side elevation on an enlarged scale of certain parts of the working mechanism, showing the needle in fully depressed stroke, and the position of the adjacent mechanism when the needle is in such position, dotted lines 45 indicating the position of parts when the needle is passing through the goods;

Fig. 4a is a view similar to Fig. 4, showing the needle going up and the parts in the positions which they assume at this stage of the operation;

Fig. 5 is a view similar to Fig. 4, showing the needle elevated to its highest position and the improved mechanism in a position for forming and completing the loop tuft;

showing the relation of certain of the working parts which are features of the present invention, namely the main gripper, the movable gripper rest and the auxiliary gripper, and showing their 5 positions relative to a stationary gripper rest;

Figs. 10, 11 and 12 are transverse vertical sections taken a short distance inside of the needle and looking to the right in Figs. 1 and 2, these 10 views being intended to illustrate the operation 10 of the needle in the formation of loops, and the severance of the latter to form tufts;

Fig. 13 is a perspective view on an enlarged scale, showing the throat plate and intended to illustrate the novel features thereof;

15 Fig. 14 is a detailed sectional view through the presser foot and throat plate, and showing the cooperating features thereof which permit goods having a line of stitching already formed thereon to pass through the machine without such stitching interfering with the operation of the needle 20 in forming a new line of stitching;

Fig. 15 on Sheet 3 is a perspective view showing the yoke mechanism employed for varying at will the length of stitches employed;

25 Figs. 16 and 17 are detail sectional views on lines 16—16 and 17—17 respectively of Fig. 2;

Fig. 18 is a detail perspective view designed to show the operation of the looper and cutter mechanism, at a time when the needle is raised, 30 and the adjacent parts of the mechanism are as indicated in Fig. 11; and

35 Figs. 19 and 20 are detail views corresponding with Figs. 10 and 11, and designed to illustrate the operation of the looper bill, and showing such looper bill and adjustable looper rest with which the bill cooperates.

General construction

The mechanism embodying the features of the 40 present invention is shown applied to a well known sewing machine, and has features in common with the apparatus described in Gladish Patent No. 1,575,570, granted March 2, 1926. As illustrated, the machine includes the usual supporting bed or base 5 (Fig. 1), an upwardly and outwardly projecting fixed arm or goose neck 6 having a head 7 at the left or forward end thereof and a main shaft 8 extending longitudinally over the bed and through the lower portion of the 45 arm 6. A driving pulley 9 is mounted on a portion of the shaft 8 extending to the right beyond the arm 6, and an eccentric 10 is mounted on the shaft adjacent the driving pulley 9. The eccentric 10 is provided with a connecting rod 11 attached to a rocker arm 12 fulcrumed on one side of the fixed arm or goose neck 6, as at 13, and having its other end clamped or otherwise secured to a needle bar 14, reciprocatingly mounted in the head 7. As usual, the needle bar 14 is 50 provided with a removable needle 15 in the lower end thereof.

The sewing machine mechanism also embodies a presser foot bar 16 provided with means for raising and lowering the bar. A presser foot 17 at the lower end of the bar 16 is of essentially 65 the usual form, which presser foot is shown in detail in Figs. 10, 11, 12 and 14. The presser foot 17 is disposed to cooperate with a throat plate 18 (Figs. 13 and 14), removably mounted 70 in a work support 19, the said work support serving also to cover the mechanism and to protect the same from dust, dirt and the like. Certain details of the throat plate are novel and this plate will be described more fully with reference 75 to the novel features hereinafter. In most of the

figures of the drawings, the work support and throat plate have been omitted so as to more clearly show the cooperation of the component parts of the mechanism.

Feeder mechanism and adjustable yoke

5

The sewing machine structure also includes a feed arm 20, clearly illustrated in Figs. 2 and 3, which arm is hinged at its rear end 127 to the hinge member of a frame 21, which frame I have 10 termed a rocker support. This frame 21 or rocker support is itself hinged at its lower portion as at 128, as illustrated in Fig. 3, so as to be free to move forwardly and rearwardly. The feed arm 20 may be swung upwardly and downwardly with 15 reference to the rocking support or frame by any suitable means cooperating with the main drive shaft 8. As shown in Fig. 3, an angularly bent strip 96 is secured to the under side of the arm 20, which strip has a horizontal portion 97 extending beneath a cam 98 on the shaft 8. The arm 20 and the horizontal portion 97 of the strip 96 thus form a yoke, which embraces the cam 98, whereby a swinging upward and downward movement is imparted to the feed arm. If 20 desired, lubricating material 95 may be provided for oiling the mechanism.

To impart forward and rearward movement to the feed arm 20, means are provided for swinging the rocking support or frame 21 about the 30 pintle 128 to which the frame is hinged. As shown in Figs. 2 and 15, the rocking frame 21 is provided with a laterally extending portion 129, enlarged as at 130, on which enlargement a yoke connection generally designated 22 is mounted 35 in such manner as to permit the yoke to swing about a vertical pivot 131.

By reason of this pivoted connection, the yoke may be swung to engage any one of a plurality of cams 23, 23a and 23b, mounted on one end of 40 the main driving shaft 8. The purpose of this yoke adjustment is to vary the stroke of the feed arm 20 and thus vary the extent of feed, dependent on the length of stitching desired. This arrangement is much simpler than the old means 45 of adjustment by means of a screw. The adjustable yoke in combination with the plurality of cams is not claimed in the present application since this feature forms the subject-matter of a copending application.

50 As shown in Fig. 15, the yoke includes a forwardly extending bar 132 which is bent downwardly so as to fit under one of the cams as indicated at 133, and said bar at its forward end is bent upwardly at 134, ending in a bifurcation 55 135. Hinged to the bar 132 at 136 is a cooperating member 137 of the yoke which is designed to extend over the proper cam member, and the forward end of such pivoted member extends through the bifurcation 135. For holding the hinged 60 member 137 in position, an arm 138 is pivotally mounted as at 139 in the bifurcation 135, and one end of the member 138 is flattened as at 140. At the other end of the arm 138 is an angular projection 141 which is designed to engage the 65 member 137 when the arm 138 is in lowered position. By raising the arm 138 so that its flattened end 140 is disposed toward the member 137, the member 137 may be raised so as to permit the yoke as a whole to be swung about the pivot 131. 70

To provide means for adjustably and yieldingly holding the yoke in operative position relative to one of the cam members, a flat spring 142 is provided which may be secured to a head 143 on the extension 129 of the rocking support 21. This 75

spring 142 carries at the opposite end a bar 144 which is provided with a plurality of grooves 145, 145a and 145b, corresponding respectively to the cams 23, 23a and 23b. This bar exerts a yielding pressure upon the lower arm 132 of the yoke member, which may be suitably engaged in any one of the grooves, depending on the length of stitching desired. The effect of the cams is to move the yoke up and down, which motion is transmitted through the enlargement 130 and extension 129 to the rocking support 21, so that the feed arm 20 will be moved forwardly and rearwardly at regular intervals, while at the same time the cam 98 previously described serves to raise and lower the arm 20, thus imparting movement in four directions to the feed arm.

The feed arm 20 carries toothed or serrated feeders 24 (Figures 2, 3 and 10 to 13) working through the throat plate 18 in the manner usual in sewing machines, the said feeders being parallel and separated by a channel or throat 25.

It will be understood from the foregoing description that the feeders 24 have four motions imparted thereto, so as to regularly engage with and disengage from the work on the work support 19, and to positively advance the work in accordance with the operation of feed devices of this class.

The sewing mechanism is also provided with a suitable tension pulley 26 (Fig. 1), mounted at the rear end of the goose neck 6. A thread or strand 27 passes first beneath said pulley 26, thence through a spring loop 26', and beneath a spring arm 28' and over tension pulley 28, on which the spring 28' is mounted. The thread is then passed through an opening 161 in a tension sleeve 158, similar to that shown in the pending application of John M. Gladish, Serial No. 220,698, filed Sept. 20, 1927. This tensioning means will be more fully described hereinafter. The thread 27 passes from the tension sleeve 158 downwardly through the eye of the needle 15 (Fig. 18).

The mechanisms described above do not involve features of the present invention, and improved attachments may be applied to various well known standard sewing machines, the one previously described being suitable and illustrating one practical application of the improvements. It will be understood, however, that the improved attachment mechanisms may be applied to other sewing machine mechanisms having essential parts similar to those described. The power for the operation of the improved attachments may be obtained direct from the main or drive shaft 8 of the sewing machine, without requiring the use of separate driving mechanism, and in the present instance, the improved attachments are applied and held by the usual base 5 of the sewing machine.

Many of the features now to be described are or may be in general similar to those shown in Gladish Patent No. 1,575,570, dated March 2, 1926, and the improvements over the said patent will be particularly referred to, such improvements cooperating in a novel manner with the features of the already existing mechanism.

Gripper operating mechanism

On the main or drive shaft 8, a cam 29 is secured (Figs. 2 and 16), which cam is engaged by a yoke 30 secured to a longitudinally shiftable rock shaft 31 mounted in bearings 32 and 33 extending upwardly from the base or bed 5. Cam 29 through the medium of the yoke 30 imparts a

rocking movement in opposite directions at intervals to the rock shaft 31.

At a suitable distance in advance of the cam 29 on the shaft 8 is a set collar 41 having a cam member 42 fixed thereto, this cam member being provided with a cam projection 43 which serves as a depressing means in connection with cooperating elements which will now be described.

Between the bearings 32 and 33 a collar 47 is secured to the longitudinally slideable rock shaft 10 31, said collar carrying an angular tappet 46, said tappet having a front right angular arm 48 which extends in parallel relation to the shaft 31.

Below the forward extremity of the rock shaft 31 is a transversely extending rock shaft 50 (Figures 1, 2, 4, and 4a) provided with an angular extremity 51 which extends under the shaft 8 and the cam member 42, the cam projection 43 of the latter member engaging the free extremity of said angular extremity 51 to depress said extremity and rock the shaft 50 at regular timed intervals. The shaft 50 also extends through the lower portion of the bearing 33, and its bearing 49 is secured to the front edge of the base 5.

Secured on the shaft 50 and projecting upwardly in front of the bearing 33 is a tappet pin 51a (Figs. 1, 2, 4, 4a and 5), which engages the free end of the arm 48, and imparts a longitudinal movement to the rock shaft 31 in the bearings 32 and 33. This results in a shifting of the yoke 30 longitudinally with reference to the cam 29, the said cam being of sufficient length to allow for the shifting of the yoke relatively thereto without disengagement from the cam member. The rock shaft 31 is longitudinally shifted against the resistance of a spring 52, which is mounted on a rod 44 extending longitudinally beyond the shaft 31, the end of said shaft 31 being hollowed out to slidably receive said rod 44. The spring 52 reacts between the yoke 30 and a nut 53 mounted on and having screw-threaded engagement with the threaded end 45 of the rod 44, said threaded end engaging a fixed stud 54 extending outwardly from the lower end of the goose neck 6. The tension of the spring may be adjusted by adjusting the nut 53 longitudinally of the rod 44. The arrangement of the tension spring 52 differs from and is an improvement over the arrangement of the corresponding elements in Gladish Patent No. 1,575,570.

The mechanism above described is designed to simultaneously impart to a loop retainer or gripper arm, 58 a reciprocating movement longitudinally of the machine and a swinging movement forwardly and rearwardly and substantially at right angles to the reciprocating movement. Said loop retainer or gripper arm 58 will now be described.

Loop retainer or gripper arm

On the end of the rock shaft 31 opposite to that on which the yoke 30 is secured, a head 55 (Figs. 1 and 2) is firmly fixed, and has a forward transverse extension 56 in which the rear end of a shank 57 of a loop retainer or gripper arm 58 is secured. This loop retainer or arm has a forward flattened holding extremity 59 with a serrated free end 60 (Figures 6 to 9). The loop retainer or gripper arm 58 is extended rearwardly by a bend 61 relative to the shank 57 and continues into said flattened extremity 59, as clearly shown in Figs. 6, 7, 8 and 9. The said loop retainer or gripper arm 58 is also extended upwardly above the plane of its shank 57 so as to properly position the flattened extremity 59 75

with its serrated free end 60 relative to an abutment means which will be subsequently described. This loop retainer or gripper arm 58 is similar to that described in Gladish Patent No. 1,575,570, 5 except that in the present device the bend 61 is rearward instead of forward, as in the patent, and its timing is slightly modified to coordinate with the additional attachments employed.

Movable gripper rest

10 According to the present embodiment, a movable gripper rest 184 is employed which oscillates with the gripper 58, this being one of the novel features of the invention. According to 15 the previous embodiments of the invention, the gripper 58 worked against a stationary stud, and it was necessary for the gripper to slide the yarn or thread on the face of the stud, whereas by 20 the use of the movable gripper rest 184 which operates in conjunction with the gripper 58, friction is avoided, and consequently more pressure may be exerted on the gripper 58 without pulling the thread out of the material which is being operated upon.

25 As shown in Figs. 2 and 17, a yoke 180 is mounted on a circular boss 181 projecting from the left-hand side of the post 33. This boss 181 is concentric with the rock shaft 31 which carries the yoke 30, but is not movable from right 30 to left as is the said rock shaft 31. The yoke 180 is provided with fingers which straddle a cam 182 mounted on the shaft 8 some distance to the left of the cam member 43, as illustrated in Fig. 2. The cam 182 is shaped similarly to the cam 29 (Fig. 16) to impart to the yoke 180 a rocking movement in synchronism with the yoke 30. The yoke 180 carries an arm 183 which extends in front of and substantially parallel with the shank 57 of the gripper arm 58. At 40 its forward end the arm 183 is bent at substantially a right angle, providing a rearwardly extending gripper rest portion 184, which moves forwardly and rearwardly in synchronism with the loop retainer or gripper arm 58. The gripper arm 58 has in addition a movement toward and from the gripper rest 184, due to the reciprocating movement which is imparted to the shaft 31 by the oscillating member 51a previously described.

50 *Additional gripper*

According to the disclosure of Gladish Patent No. 1,575,570, the gripper 58 alone was employed, 55 whereas according to the present invention an additional gripper is employed which cooperates with the gripper 58, the two devices forming a double gripper which hold the yarn during different stages of the loop forming operation, and prevent the same from pulling through the material which is being sewed. The additional gripper has a swinging or oscillating movement about a vertical pivot, and swings toward and from a fixed abutment or gripper rest 104, which 60 will be more fully described hereinafter, but has no movement at right angles to the swinging movement.

As shown in Fig. 3, a sleeve 185 is mounted on a post or vertical pivot 186, and from the lower portion of the sleeve there extends a lever 70 arm 188 at the end of which is a contact member 189 (Fig. 2), which engages a cam 190 on the main shaft 8 at a point slightly to the left of the yoke 180 which operates the gripper rest. The cam 190 through the medium of lever arm 75 188 rocks the sleeve 185 about the pivot 186,

and when the sleeve 185 is rocked an arm 191 secured to the upper portion of the sleeve is oscillated to and fro. At the forward end of the arm 191 there is a bend 192 (Fig. 6), the bent portion 193 (Figures 6 to 9) forming an auxiliary gripper arm which is serrated as at 193', forming teeth similar to the teeth 60 of the gripper 58.

The auxiliary gripper arm 193 is moved in one direction by means of the cam 190 previously described, and in the other direction by means of a compression spring 197. As shown in Fig. 2, a rod 194 extends laterally from the arm or shank 191, the end of the rod opposite said shank being slidable through a post 196. The compression spring 197 surrounds the rod 194 between the post 196 and a nut 198 on a screw-threaded portion of the rod 194. Suitable adjustment of the compression of the spring may be secured by rotating the nut 198 on the rod 194. Thus 20 the cam 190 moves the gripper arm 193 away from the abutment 104, while the spring 197 moves it in the opposite direction.

Cutter and looper rock shafts

25

Referring further to features substantially in common between the present device and Gladish Patent No. 1,575,570, it will be noted that a short distance in advance of the bearing 49 (Fig. 2) a pair of bearing members 62 are secured both at the front and rear portions of the bed or base 5, and therein are mounted transversely extending parallel rock shafts 63 and 64 designed primarily for operating the cutter and looper mechanisms respectively. The shafts 63 and 64 extend under and at right angles to the main drive shaft 8. Secured on the shaft 8 above the rock shaft 63 is a cam cylinder 65 having a cam groove 66, and secured on the shaft 63 is a rocking head 68 (Figs. 3 and 4) with a side extension 69 having an opening 70 in which a rearwardly projecting pin 71 is mounted, the said pin engaging the cam groove 66 of the cylinder 65 and being held in the opening 70 by a set screw 72 inserted in the side-extension 69.

40 From the above description it will be obvious that rotation of the main drive shaft 8 will, through the medium of the cam cylinder 65 and the cam groove 66, serve to oscillate the rock shaft 63.

45 On the shaft 64 is secured a tubular rocking head 81 (Figs. 1, 2 and 4) having an angular actuating arm 82 (Fig. 2) extending rearwardly therefrom and beneath the main drive shaft 8 and under a cam member 83 fixed to or forming part of a cam collar 84 secured on the main drive shaft 8. Thus the movement of the drive shaft also oscillates the shaft 64.

50 The principal function of the shaft 63 is to operate a cutter mechanism 75 and also a movable needle guide bar 200, both of which will be subsequently described. Similarly, the principal function of the shaft 64 is to operate a looper 92, which will be described in detail hereinafter.

55 Cams 66 and 83 on the main drive shaft 8 serve to oscillate the shafts 63 and 64 in one direction and suitable coil springs 77 and 85 (Fig. 2) are provided for rocking the shafts 63 and 64 in the opposite direction. As shown, spring 77 is 70 mounted on shaft 63 adjacent the forward portion thereof, and one end is looped about a pin 211 extending from a collar 209 fixed to the end of the shaft 63. A similar collar 210 is mounted on the shaft 64, and one end of spring 85 engages 75

a pin 212 mounted on this collar. The opposite ends of both springs 77 and 85 are looped about a short cross rod 213, which connects and holds in fixed relation two collars 214 and 215 which are loosely mounted on the shafts 63 and 64 respectively. These collars 214 and 215 are separated from the bearings 62 on the frame member by means of spacing sleeves 216 and 217 secured to the shafts 63 and 64 respectively. The tension of the springs 77 and 85 serves to hold the actuating devices 71 and 82 which operate the shafts 63 and 64 firmly against their respective cam members 66 and 83, and as soon as said actuating devices ride off of the projections of the cams, the springs 77 and 85 rock the shafts in the opposite direction.

Extending upwardly from the rocking head 68 on shaft 63 is a cutter supporting arm 73 (Figs. 1, 3 and 4) having a suitable screw threaded opening in the free extremity thereof to receive a set screw 74, this screw also passing through a reversible rectangular shaped knife or cutter 75, as shown in Figs. 4, 4a and 5. When it is desired to cut the loops as formed, the knife or cutter 75 will be secured and firmly held in the free extremity of the arm 73, but when it is desired to produce a tufted fabric with uncut loops, the knife or cutter 75 may be removed by disengaging the set screw 74 from the extremity of the arm 73. The upper and lower edges of the knife or cutter 75 are similarly sharpened and when one edge becomes dull, the knife may be reversed to bring into operation its opposite sharper edge, thereby materially saving time in the effective operation of the machine or the cutting implement of the latter. It will also be understood that a number of these knives or cutters 75 will be furnished as a part of the equipment of the machine, and a new cutter may be readily applied to the arm 73 to replace another in the event of excessive wear, and moreover, any one of the cutters may be sharpened to a certain extent without impairing the operation of the cutting mechanism.

45   Needle guide

One of the features of the present invention rendered necessary by the use of the oscillating gripper rest 184, in place of the stationary rest as in Gladish Patent No. 1,575,570, is an oscillating needle guide bar 200, which moves over to the left rearwardly of the needle 15 at such time as the gripper arm 58 and gripper rest 184 are together moving rearwardly. This position is clearly illustrated in Fig. 4 of the drawings, and at such time the bar 200 acts as a guide for the lower portion of the needle and prevents it from being moved out of alignment by the action of the members 58 and 184 referred to above, which might otherwise have a tendency to pull the needle out of vertical position. As soon as the needle is raised and the cutter 75 comes into position for severing the loops of yarn, the needle guide is moved to the right and out of the way of the cutter.

As shown in Fig. 3, the needle guide bar 200 is mounted on the end of a horizontal shaft 201, which is secured in an extension of a sleeve 202, which sleeve is located just in front of the sleeve 185 which operates the auxiliary gripper arm. Sleeve 202 is mounted on a vertical post 203, and is adapted to be oscillated thereon. To impart movement to the guide bar, an extension 204 of said bar is provided with an aperture 205. Rig-
70   idly mounted on the shaft 63 is a collar 206 which

is provided with a radially extending oscillating finger 207 having a rearwardly bent portion which passes through the aperture 205, and in this manner oscillation of the shaft 63 serves to oscillate the needle guide bar 200 in timed relation to the needle 15 and cutter 75.

5   Looper mechanism

As heretofore described, there is secured on the shaft 64 a tubular rocking head 81 having an angular actuating arm 82 extending rearwardly therefrom beneath the main drive shaft 8 and under a cam member 83 fixed to or forming a part of a cam collar 84 secured on the main drive shaft 8, as shown in Figures 2, 4 and 4a.

In the tubular head 81 a shank 89 is secured, which has on the upper extremity thereof a looper hook or extended bill 90. This hook includes a rearwardly extending looped portion 91 with an outwardly projecting tapered bill 92, which is reduced to a point at 93 (Figs. 18, 19 and 20), and is so proportioned and generally shaped as to cooperate closely with the needle 15 and with surely pass through the looped thread or strand lowered with the needle, the outer edge of the loop or bill 92 moving close to the rear portion of the needle and with nicety passing between the needle and the portion of the thread or strand at the rear thereof to retain a part of the thread in lowered position so as to produce the loop when the needle moves upwardly. When the looper, as just explained, reaches the outer limit of its stroke (shown in Figure 5) and has performed its function, the arm 82 will pass over the high portion of the cam member 83, and the spring 85 will instantly elevate the arm 82 and rock the head 81, the shank 89 and the looper hook or bill 90 in the opposite direction into its outermost position shown in Fig. 4, the intermediate position of the looper mechanism being illustrated in Fig. 4a. The bill 90 is similar to that shown in Gladish Patent No. 1,575,570, but in the present instance is not slotted at the forward end thereof as shown in the patent.

45

Fixed gripper rest and looper rest

At the left of the machine adjacent the cams 23, 23a and 23b, a post 100 extends upward from the base 5 and carries abutment members 103 and 104 (Fig. 4). In Gladish Patent No. 1,575,570 these abutment members were in one piece, but according to the present embodiment of the invention two separate pieces are employed which are known, respectively, as the gripper rest 104 and the looper rest 103. As shown in Fig. 2, the abutment member 104 is in the form of a bar bent intermediate its ends and secured by means of a screw 101 to the top of the post 100. This abutment member extends just short of the path 60 of the needle 15 and forms a fixed abutment for the additional gripper 193, previously described (see Figs. 6, 7, 8 and 9).

The abutment 103 is carried by a bolt 105 extending through a vertical slot 102 in the post 65 and engaging said abutment as at 106. Thus said abutment may be raised or lowered slightly by releasing said bolt and moving it upwardly or downwardly in the slot 102 and again tightening it. The abutment 103 is shaped so as to permit the cutter 75 to just pass the same. Its position is adjusted so as to allow the looper 92 to pass over it and to provide a snug fit between the two members (see Figs. 18 and 20). By making the abutment 103 vertically adjustable and 70 75

separate from the gripper rest 104, a very close fit may be secured.

Presser foot and throat plate

5 The presser foot 11 and throat plate 18 function substantially as in the ordinary sewing machine, but in the present instance each element is modified somewhat to prevent rows of stitches previously made in the goods from getting in the 10 way of the needle when another line of stitching is being made. The presser foot and throat plate are shown in detail in Figs. 10 to 14 inclusive. In the remaining figures the throat plate and work support have been removed in order to disclose 15 the working mechanism. As shown in Fig. 13, the throat plate 18 is substantially rectangular in shape and is secured in any suitable manner to the work support 19. The rectangular slot 107 is formed in the throat plate to permit the forward end of the feed arm 20 and the feeders 24 to move freely therethrough. At the end of the throat plate opposite the slot 107 a tongue 108 is provided, having short narrow slots 109 (Figure 13) at the sides thereof into which the work 20 feeders 24 enter, and a central slot 110 through which the needle 15 passes. The tongue 108 has been specially designed in the present instance to guide rows of stitches previously made in the goods, and to prevent them from getting in the 25 way of the needle while another line of stitching is being made. As shown, the tongue includes a rounded raised portion 218, at the sides of which are grooves 219. As indicated in Fig. 14, the presser foot 11 is similarly modified, being provided with a downwardly extending rounded tongue 220 with grooves 221 at each side thereof, which mate with the grooves 219 in the throat plate and provide free avenues of approach for 30 lines of stitching A already made in the fabric B, while the fabric is being presented to the needle 15 for forming a new line of stitching at a point midway between the two grooves 219. Thus the raised tongue or boss on the throat plate presses the lines of stitching on either side of same into the grooves and effectively keeps them out of the 35 way of the needle in making a new line of stitching.

Presser foot bar releasing mechanism

50 The upper portion of the presser foot bar 16 is engaged by the forward end of a lifting lever 115 fulcrumed as at 116 on the rear portion of the goose neck 6. This lever has a bar 117 attached to and extending rearwardly from the rear 55 end thereof. A link 118 has its upper end connected to the rear end of the bar 117 and its lower end connected as at 119 to the rear end of a lever 120, which extends to the left, as shown in Figs. 1 and 2, and is bent at 121, the bent portion being journaled in bearings 122. The lever 120 is again bent to the right as shown at 123, and then forwardly as at 124, the portion 124 extending beneath the projection 43 of the cam 42. The presser foot bar 16 is engaged by a flat spring 125 secured to the rear part of the upper portion of the goose neck 6 as at 126, as shown in dotted lines in Fig. 1. The purpose of this combination of levers and the spring 125 is to raise the presser foot bar 16 and presser foot 11 in regular timed 60 relation to the operation of the cam 42, and consequently in definite relation to the working parts of the machine. By means of this arrangement, the presser foot is raised to ease the feed of the fabric by the feeders 24 as it is being tufted. 65 This easing movement of the presser foot through

the mechanism just described is slight, and against the resistance of the spring 125 which always tends to force the presser foot bar 16 and presser foot 11 downwardly. At any time the lever 115 may be manually rocked by depressing the rear end of the bar 117 to raise the presser foot 11 and the presser foot bar 16, particularly when arranging the work in position or disposing the fabric to be tufted between the presser foot and the feeders. This operation is similar to that described in Gladish Patent No. 1,575,570. 10

Thread tensioning mechanism

The thread tensioning mechanism has been 15 briefly referred to, and as shown is similar to that set forth in Gladish Patent No. 1,800,522, granted April 14, 1931, except that the tensioning mechanism in the present device is designed for use with a single needle and single thread, while in 20 the application referred to a plurality of needles with a plurality of strands are employed. The purpose of the tensioning means is, of course, to maintain the thread in taut condition during the formation of the loops. 25

As shown in Fig. 1, a clamping or holding means for the thread 27 is located in the upper front portion of the goose neck 6. This device comprises a forwardly projecting bearing 155 located at the right of the machine, in which is mounted one extremity of a longitudinally shiftable slide rod 156 of which the end portion 157 is shiftable within a sleeve 158. This sleeve has at its forward end a tubular head 159 which is supported by a crook arm 160 secured to the upper part of the head 7 of the arm or goose neck 6. The sleeve 158 has a transverse opening 161 therethrough, which is adjacent the end portion 157 of the rod 156. On the rod 156 is a set collar 162 engaged by one extremity of a spring 163 surrounding the said rod and engaging at its opposite extremity with the bearing 155. The spring 163 urges the rod 156 to the left (Figure 1) and tends to restore the rod 156 to its normal position after it has been reciprocated and thus holds the 45 thread, which passes through the opening 161, between the end 157 of the rod 156 and the solid end portion of the sleeve 158. In advance of the vertical member of the arm or goose neck 6 is a vertical rock shaft 164 having its lower end journaled, as at 165, in the bed 5. The upper end of the rock shaft 164 carries a crank 167 which has an upper horizontal forwardly projecting terminal member loosely fitting in a slot 169 in the free end of a longitudinal arm 170 of an angle 55 bracket extending from a collar 172 secured on the rear end of the rod 156.

For operating the rock shaft 164 a collar 173 is mounted at the lower portion thereof, and has a curved finger 174 projecting therefrom under the rear extremity of the rod 44, with its end bearing against the periphery of a cam 175 on the rear portion of the shaft 8, said cam 175 having a projection, which, when it engages the end of the finger 174, forces the latter outwardly 65 and rocks the shaft 164.

The operation of this tensioning device will be evident from the foregoing description and serves to hold the thread taut while the loops are being formed in the goods, but automatically releases 70 the thread or yarn in time for the taking of another stitch, the whole operation being automatically timed in definite relation to the other operations of the machine, by reason of the fact that the cam which operates the tensioning device is 75

mounted on the main driving shaft which carries the cams for timing all the operations of the machine.

General operation

The operation of the device is similar in many respects to that of the machine set forth in Gladish Patent No. 1,575,570 and is designed to form similar tufts. The same series of operations takes place as in the patent, and the elements common to the two machines operate in a similar manner. Since the principal features of novelty in the working mechanisms of the present device are the movable gripper rest 184 and the additional gripper 193, the description of the operation of the present machine will be with a view to rendering clear the functions of these novel elements and their cooperation with the other elements of the machine, it being understood that such old elements operate substantially in the manner described in the patent referred to. Figs. 6 to 9 inclusive are diagrammatic views designed particularly to show the relative movements of the gripper 59, the additional gripper 193 and the gripper rest 184, the stationary gripper rest 104 with which the gripper 193 cooperates being likewise indicated to show the changes in the relative positions of the parts during the operation of the machine. Figs. 4, 4a and 5 are side elevations likewise designed to show the relative movements of the working parts. Figs. 10, 11 and 12 are detailed sectional views showing the varying relations of parts during the different operations of the mechanism. With these figures in mind, the operation of the device will be evident from the following description.

Assuming that one stitch has already been made in the fabric and that the needle 15 has been raised to its uppermost position, as shown in Figure 5, the looper hook 90 will extend between the portions of the previously-formed loop which have been cut by the knife 75, of which the cutting edge will extend into the slot of the looper hook, both portions of the cut loop will be gripped between the gripper 58 and its associated rest 184 immediately below the needle, the gripper 193 will be positioned against its associated rest 104, as shown in Figure 6, the presser foot 17 will be in its raised position, the feeders 24 will be in their rearmost position, and the slide rod 156 will grip the thread. As the needle starts to descend to again penetrate the fabric, the slide rod 156 will be caused to release the strand, the feeders 24 will be moved forwardly, the presser foot 17 will be lowered, the gripper 58 and its associated rest with the portions of the severed loop between them will be moved rearwardly below the gripper 193 and gripper rest 104 to place the portions of the loop which has just been cut between the gripper rest 104 and gripper 193, which will then be separated, as shown in Figure 7. At the same time the looper hook 90 will be moved out of the path of the needle 15. As the needle continues to descend and just before it commences to penetrate the fabric, the needle guide bar 200 will be moved behind the needle to guide the needle and the looper hook 90 will have been moved out of the path of the needle, as shown in Figure 4a. When the needle has descended to its lowermost position the looper hook 90 will have been fully retracted, as shown in Figure 4, the gripper 193 will have been moved against its rest 104 to grip the ends of the previously-formed and cut loop,

and the gripper 59 and its rest 184 will be positioned, respectively, immediately below the gripper 193 and rest 104, as shown in Figure 8.

As the needle commences to rise, the gripper 59 will be moved away from its rest 184 to release the portions of the cut loop and it, together with the rest 184, will be moved toward the front of the machine into the position shown in Figure 9. During this movement of the gripper 59 and rest 184 the looper hook 90 will enter between the needle and the thread to form another loop, as shown in Figure 4a, the presser foot will be raised, the feeders 24 will be moved upwardly and rearwardly to advance the fabric, the slide rod will be caused to grip and apply tension to the strand, and just before the needle reaches its uppermost position shown in Figure 5 the gripper 59 will be caused to again move against its rest 184 immediately below the needle to grip the newly-formed loop, as shown in Figure 6, and the knife 75 will have been moved upwardly into the longitudinal slot of the looper hook 90 into the position shown in Figure 5 to sever the loop. Thereupon the operations just described will be repeated.

The stroke of the feeders 24 may be varied as desired by engaging the yoke 22 with any desired one of the cams 23, 23a or 23b. The tension of the thread may be adjusted as desired by adjusting the set collar 162 longitudinally of the slide rod 156 to obtain the desired tension of the spring 163.

All the parts of the mechanism operate in complete synchronism, and very satisfactory practical results are obtained.

What I claim is:

1. In a machine of the character described, the combination with a reciprocating needle, means for guiding a strand thereto, loop forming mechanism, comprising a fixed abutment, a reciprocating looper bill movable toward and from said abutment, a pair of separately movable gripper arms and abutments with which said gripper arms cooperate for holding portions of successive loops during operation of the needle to produce successive loops of uniform dimensions.

2. In a machine of the class specified, the combination with a reciprocating needle, means for guiding a strand thereto, loop forming mechanism, comprising a looper bill, and means for holding portions of successive loops during the operation of the needle to produce successive loops of uniform dimensions, said means comprising a gripper rest and a gripper arm having a reciprocating movement toward and from said gripper rest, said gripper rest and gripper arm having a swinging movement in synchronism substantially at right angles to the movement of the looper bill.

3. In a machine of the class specified, the combination with a reciprocating needle, means for guiding a strand thereto, loop forming mechanism, comprising a looper bill, and means for holding portions of successive loops during the operation of the needle to produce successive loops of uniform dimensions, said means comprising a gripper rest and a gripper arm having a reciprocating movement toward and from said gripper rest, said gripper rest and gripper arm having a swinging movement in synchronism and substantially at right angles to the reciprocating movement of the gripper arm, a swinging cutter for severing loops formed from the strand, and a rest for supporting the lower end of the needle while in lowered position, said rest being movable

out of the path of the cutter during the cutting operation.

4. In a machine of the class specified, the combination with a reciprocating needle, means for guiding a strand thereto, loop forming mechanism, comprising a looper bill, and means for holding portions of successive loops during the operation of the needle to produce successive loops of uniform dimensions, said means comprising a gripper rest and a gripper having a reciprocating movement toward and from said gripper rest, said gripper rest and gripper having a swinging movement in synchronism substantially at right angles to the reciprocating movement of the gripper, a stationary gripper rest, and an additional gripper having a reciprocating movement toward and from said stationary rest.

5. A sewing machine including a reciprocating needle and means for guiding a strand to the latter, a normally fixed looper abutment, a looper having a swinging movement toward and away from said abutment and partially movable over the latter with a snug fit between the two, said abutment being adjustable to insure such close fit, and loop holding mechanism including a gripper rest and a main gripper arm unitarily movable in the direction of movement of the goods in which the loops are being formed, said gripper arm having also a reciprocating movement toward and from the gripper rest for periodically gripping and releasing portions of successive loops at different stages of the operation of said needle, a stationary abutment above the looper abutment, and an auxiliary gripper arm movable toward and away from said second abutment and operating at different intervals than the main gripper.

6. A sewing machine including a reciprocating needle and means for guiding a strand to the latter, a normally fixed looper abutment, a looper having a swinging movement toward and away from said abutment and partially movable over the latter with a snug fit between the two, and loop holding mechanism including a gripper rest and a main gripper arm unitarily movable in the direction of movement of the goods in which the loops are being formed, said gripper arm having also a reciprocating movement toward and from the gripper rest for periodically gripping and releasing portions of successive loops at different stages of the operation of said needle, a second stationary abutment above the looper abutment, and an auxiliary gripper arm movable toward and away from said second abutment, and operating at different intervals than the main gripper, and a loop cutting mechanism cooperating with said loop forming and holding mechanisms, for severing the successive loops from the main strand carried by the needle while the needle is in raised position and while the loop is engaged by said holding mechanism.

7. In a machine for forming successive loops in intermittently advanced work material, a main loop gripper arm, and a gripper rest having a swinging movement to and fro in the direction of movement of the work material, said gripper arm also having a reciprocating movement to and from the gripper rest for periodically gripping successive loops being formed in the work material, a stationary gripper rest and an auxiliary loop gripper arm having a swinging movement toward and from the stationary rest at intervals different from the reciprocating movement of the main gripper arm.

8. In a machine of the character described, a work support to receive a fabric thereon, a vertically reciprocating strand-carrying needle movable through the work support and fabric, means for intermittently advancing the fabric relative to the work support, loop forming means cooperating with the needle for intermittently forming successive loops in the fabric from a strand carried by the needle while the needle is in lowered position, and two sets of loop retaining devices adapted jointly to hold portions of successive loops during different periods of loop formation, one set of loop retaining devices comprising a gripper rest and a main gripper arm unitarily movable with the movement of the fabric advancing means, said gripper arm having also a reciprocating movement toward and from the gripper rest, the second set of loop retaining devices including a fixed abutment and an auxiliary loop gripper movable to and from the fixed abutment at different intervals than the reciprocating movement of the main gripper arm.

9. In a machine of the character described, a work support to receive a fabric thereon, a vertically reciprocating strand-carrying needle movable through the work support and fabric, means for intermittently advancing the fabric relative to the work support, loop forming means cooperating with the needle for intermittently forming successive loops in the fabric from the strand carried by the needle while the needle is in lowered position, and two sets of loop retaining devices adapted jointly to hold portions of successive loops during different periods of loop formation, one set of loop retaining devices comprising a gripper rest and a main gripper arm unitarily movable simultaneously with the movement of the work feeding means, said gripper arm having also a reciprocating movement toward and from the gripper rest, the second set of loop retaining devices including a fixed abutment and an auxiliary loop gripper movable to and from the fixed abutment at different intervals than the reciprocating movement of the main gripper arm, and loop cutting means operating in timed relation to the loop forming means for severing the loops from the strand carried by the needle.

10. In a machine of the character described, a work support to receive a fabric thereon, a vertically reciprocating strand-carrying needle movable through the work support and fabric, means for intermittently advancing the fabric relative to the work support, loop forming means cooperating with the needle for intermittently forming successive loops in the fabric from the strand carried by the needle while the needle is in lowered position, and two sets of loop retaining devices adapted jointly to hold portions of successive loops during different periods of loop formation, one set of loop retaining devices comprising a gripper rest and a main gripper arm unitarily movable simultaneously with the movement of the work feeding means, said gripper arm having also a reciprocating movement toward and from the gripper rest, the second set of loop retaining devices including a fixed abutment and an auxiliary loop gripper movable to and from the fixed abutment at different intervals than the reciprocating movement of the main gripper arm, and loop cutting means operating in timed relation to the loop forming means for severing the loops formed from the strand carried by the needle, and means for actuating said moving parts in timed relation one to the other to avoid interference one with another.

11. In a machine of the character described, the combination with a reciprocating needle, means for guiding a strand thereto, loop forming mechanism comprising a reciprocating looper bill, a pair of gripper rests, a pair of separately movable gripper arms cooperating, respectively, with said gripper rests for holding portions of successive loops formed by said looper bill from the strand carried by the needle during operation of the needle, and a loop cutting device operating in timed relation to, but moving in opposite directions from said looper bill, for successively cutting loops formed by said looper bill from the strand carried by the needle.
12. In a machine of the class specified, the combination with a reciprocating needle, means for guiding a strand thereto, loop forming mechanism comprising a looper rest, a looper bill movable toward and from the looper rest, and means for holding portions of successive loops during the operation of the needle to produce successive loops of uniform dimensions, said means comprising a gripper rest and a gripper arm having a reciprocating movement toward and from said gripper rest, said gripper rest and gripper arm having a simultaneous swinging movement at substantially a right angle to the reciprocating movement of the gripper arm, and a loop cutting device mounted to swing on a fixed axis and operating in timed relation to the looper bill, but in opposite directions from the latter, for severing successive loops formed by the looper bill from the strand carried by the needle.
13. In a machine of the class specified, the combination with a reciprocating needle, means for guiding a strand thereto, loop forming mechanism comprising a looper rest, a looper bill movable toward and from the looper rest, and means for successively holding loops formed by said looper bill during each reciprocation of the needle from the strand carried by the needle, said means comprising a gripper rest and a gripper arm having a reciprocating movement toward and from said gripper rest, said gripper rest and gripper arm being unitarily movable substantially at a right angle to the direction of movement of said looper bill and transversely of the path of movement of the needle during each rising movement of the needle and said gripper arm being movable relatively to said gripper rest substantially at a right angle to said first direction of movement, the unitary movement of said gripper rest and gripper arm and the movement of said gripper arm relatively to said gripper rest being so timed with reference to the movement of the needle that the gripper arm is out of the path of the needle during the descent of the needle.
14. In a machine of the class specified, the combination with a reciprocating needle, means for guiding a strand thereto, loop forming mechanism comprising a looper rest and a looper bill movable toward and from the looper rest and operative during each reciprocation of the needle to form a loop from a strand carried by the needle, means for holding each loop as formed, said means comprising a gripper rest and a gripper having a reciprocating movement toward and from said gripper rest, said gripper rest and gripper having a unitary swinging movement substantially at a right angle to the reciprocating movement of the gripper, a stationary gripper rest, an additional gripper having a reciprocating movement toward and from said stationary rest, and a cutting mechanism cooperating with the loop forming and holding mechanisms and operative to sever each loop as formed while it is held by the first-named gripper rest and gripper arm.
15. A sewing machine comprising a work support, a throat plate, feeding devices working through said throat plate, said throat plate being adapted to support a fabric having lines of already formed stitching thereon, and means including a reciprocating needle for forming a line of stitching in the fabric, said throat plate having a tongue slotted at its free end to permit passage of the needle therethrough, a groove on each side of said tongue and a raised boss adjacent the other end of said tongue for separating lines of already formed stitches and directing the same into said grooves and keep said stitching out of the way of the needle.
16. In a device of the character described, a throat plate including a tongue having a needle receiving slot at one end thereof, said plate having a raised boss at the other end of the tongue, and grooves on opposite sides of the raised boss.
17. A throat plate for sewing machines, comprising a rectangular plate having a rectangular slot to receive fabric feeding devices, said throat plate also having a tongue extending from one end of said slot, said tongue being slotted at its free end to permit reciprocation of a needle therethrough, said plate having on its upper surface a boss adjacent the end of said tongue opposite the needle slot and grooved portions at the sides of the raised boss.
18. In a machine of the character described, including a reciprocating needle adapted to pass through a fabric, means for guiding a strand to said needle, and a loop forming mechanism adapted to form a loop in the thread carried by the needle after the latter passes through the fabric, means for holding and moving said loop in the direction of movement of the fabric in the machine, means operative to hold the loop after it has been moved by said first mentioned holding means, during the remainder of the reciprocation of the needle in completing the succeeding loop, a cutter operative to cut the loop while it is on the loop-forming mechanism, and a needle guide movable into position to guide the needle after it has passed through the fabric and movable out of the way of the cutter when the needle is withdrawn from the fabric.
19. In a machine of the class specified, including a work support, a reciprocating needle adapted to carry strands through the work support and the work thereon and means for guiding a strand to the needle, and a looper adapted to form a loop in the strand carried by the needle beyond the work support, gripping means operative to grip such loop and move it in the direction of movement of the work in the machine, and means cooperating with said gripping means for holding said loop during the entire reciprocation of the needle in the formation of the succeeding loop.
20. In a machine of the class specified, including a reciprocating needle operative to carry a strand through a work support and the work thereon, means for guiding the strand to said needle, and a looper operative to form a loop in the strand carried by the needle beyond the work support, loop gripping means comprising a gripper operative to grip a strand of the said loop and move it in the direction of movement of the work in the machine, and a second loop gripping means operative to grip and retain the said strand.

- strand in its new position while the first mentioned gripper returns to its position to grip the next loop.
21. A machine as defined in claim 20, including a cutter operative to cut said loops.
22. A machine as defined in claim 20, in which the second loop gripping means is positioned between the work and the first mentioned gripper at the completion of the movement of the latter in the direction of the movement of the work.
23. In a machine of the class specified, the combination with a reciprocating needle adapted to pass through work in the machine, of a looper movable toward and from the position of the needle after the latter passes through the work and having a slot therein, a cutter movable into said slot to cut the loop on the looper, and a needle guide movable into position beside the needle after the needle passes through the work and movable therefrom as the needle is withdrawn and before the cutter moves into said slot.
24. In a machine of the class specified, the combination with a reciprocating needle adapted to pass through work in the machine, a looper movable toward and from the position of the needle after the latter passes through the work and having a slot therein, a cutter movable into said slot to cut the loop on the looper, and a needle guide movable into a position beside the needle on the side of the needle away from the direction of feed of the work and movable from such position when the needle is withdrawn to permit the cutter to move into said slot.
25. In a machine of the class specified, the combination with a reciprocating needle adapted to pass through work in the machine, of a looper movable toward and from the position of the needle after the latter passes through the work, a cutter movable toward and from the looper to sever the loops thereon and a reciprocating needle guide adapted to contact with the side of the needle opposite to the direction from which the work moves.
26. In a machine of the class specified, including a work support, a reciprocating needle adapted to pass through said work support, means for guiding a strand to said needle, and a looper adapted to form a loop in the strand carried by the needle beyond said work support, loop gripping means comprising a gripper arm fixed against movement laterally of the needle and a second gripper arm mounted to reciprocate laterally of the needle, said gripper arms being mounted to rock on a common axis, in the direction of movement of the work through the machine, and means for separately rocking said gripper arms.
27. In a machine of the class specified, the combination with a reciprocating needle adapted to pass through work in the machine, of a looper movable toward and from the position of the needle after the latter passes through the work, a cutter movable toward and from the looper to sever the loops thereon and a reciprocating guide adapted to contact with the needle after it passes through the work.
28. In a machine of the character described, including a reciprocating needle adapted to pass through a fabric, means for guiding a strand to said needle, and a loop forming mechanism adapted to form a loop in the strand carried by the needle after the latter passes through the fabric, a gripper arm adapted to reciprocate laterally of the path of the work to a position adjacent a fixed abutment and means for holding and moving a strand of said loop into the path of reciprocation of said gripper arm.
29. In a machine of the class specified, the combination with a reciprocating needle adapted to pass through work in the machine, of a looper movable toward and from the position of the needle after the latter passes through the work, said looper having a slot therein and a cutter adapted to move into said slot to cut the loops, means for holding and moving the loops in the direction of movement of the work and a gripper adapted to retain the loops in their advanced position.
30. In a machine of the class specified including a reciprocating needle, a looper movable toward and from the position of the needle after the latter passes through the work, loop gripping means comprising a gripper arm adapted to reciprocate laterally of the path of movement of the work to a position adjacent an abutment and a pair of grippers adapted to grip strands of the loops and move them forwardly into the path of reciprocation of the first mentioned grippers.
31. In a machine of the class specified including a reciprocating needle, a looper movable toward and from the position of the needle after the latter passes through the work, loop gripping means comprising a gripper adapted to grip a strand of the loop after the needle is withdrawn from the looper and to move the same forwardly out of the path of the needle, and a second gripping means adapted to grip the strand in its advanced position while the first mentioned loop gripping means returns to its position to grip the strand of the next loop.
32. In a machine of the class specified including a work support, a reciprocating needle, a looper adapted to form a loop in a strand carried by the needle beyond the work support, means for holding and moving a strand of said loop in the direction of movement of the work through the machine, and means for gripping a strand of said loop while the said holding and moving means returns and grips a strand of the next loop.
33. A machine as defined in claim 32, in which the looper is slotted and a cutter is provided to pass into said slot and cut a loop on the looper.
34. In a machine of the class specified including a work support, a reciprocating needle, a looper adapted to form loops in a strand carried by the needle beyond the work support, a gripper adapted to hold and move a strand of the loop in the direction of movement of the work in the machine and a gripper adapted to retain the strand of said loop passing through the needle until the said first mentioned gripper returns to its position and grips a strand of the next loop.

JULIAN GUY RUSSELL.
